UNITED STATES PATENT OFFICE.

HOWARD E. STILES, OF BOLIVAR, MISSOURI.

GRAVEL LOADER.

Application filed December 31, 1921. Serial No. 526,207.

To all whom it may concern:

Be it known that I, HOWARD E. STILES, a citizen of the United States, residing at Bolivar, in the county of Polk and State of Missouri, have invented new and useful Improvements in Gravel Loaders, of which the following is a specification.

The general object of this invention is to provide means for facilitating the loading of trucks, cars and the like, with gravel and other materials by providing an inclined track and a car traveling thereon and arranged to receive the material at the lower part of the track and to transport it to the elevated part where it can be dumped into the receiving vehicle.

Another object of the invention is to provide means for automatically tilting the car at the elevated end of the track so that the material therein will be dumped into the receiving vehicle which is located below the elevated end of the track.

A further object of the invention is to provide a single operating cable for pulling the car up the track, for controlling the dumping action and for returning the parts to their normal position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

40 Figure 1 is a plan view of the invention showing the car in load receiving position.

Figure 2 is an elevation showing the car with the sides raised and ready to be pulled up the inclined track.

45 Figure 3 is a similar view with the parts in dumping position.

Figure 4 is a detail view showing the safety device.

Figure 5 is an end view showing portion 50 of the dumping section in dumping position with the member 13 in section.

Figure 6 is a sectional view through one of the rails and through a portion of the dumping section.

Figure 7 is an elevation showing the locking means for the dumping section. 55

Figure 8 is an end view of such means with parts in section.

Figure 9 is a view of the cam of such means. 60

Figure 10 is a view of the bolt of such means.

In these views 1 indicates a framework for supporting the rails 2 in an inclined position. A wheeled frame 3 is adapted to travel upon the rails and this frame supports a body 4. The rear end of this frame is provided with an upright piece 5 and the sides 6 of the body are hinged so that they can be swung downwardly to form continuations of the floor or upwardly to hold the material upon the body. They are held in upright position by means of the hooks 7. The front end of the car is left open. Inclined platforms 8 are arranged at the small end of the frame 1, one at each side thereof so that a car or other vehicle can pass from the ground upon the body when the sides of the body are lowered, so as to dump the load upon said body. After a load has been placed upon the body the sides are swung upwardly and hooked in position. 70

The elevated end of the frame 1 is of sufficient height to extend well above a truck, car or other load receiving element located at the elevated end of the track so that the load from the body can be dumped into the said vehicle from the upper end of the track. 85

The upper end of the track is formed with a dumping section 9, the side bars of which are made to embrace the upper ends of the rails and form continuations of the track. This section is pivotally secured to the high end of the frame by means of the rod 10 and this section is provided with a central beam 11 which extends downwardly below the end of the section and is provided with a depending part 12 which is adapted to engage a recessed member 13 supported by the frame. A pair of pulleys 14 are located in the member and a pulley 15 is carried by the depending part 12 and a guiding pulley 13' is placed in a recess in the beam, the pivot of which is formed by the rod 10. A cable 16 is passed around said pulleys and has one end fastened to the wheeled frame 3 and its other end is adapted to be fastened to any power appliance or 95

a team so as to pull the wheeled frame and body up the track. Stops 17 are arranged on the dumping section for engaging the front wheels of the wheeled frame to prevent further movement of said frame.

After the load has been placed upon the body the sides thereof are swung upwardly and hooked in position. The cable is then pulled upon so as to pull the wheeled frame and its body up the track. When the front wheels strike the stops 17 further movement of the wheeled frame will be prevented and the weight of the parts and load will cause the pivoted section of the track to tilt and thus discharge the load into the wagon or other vehicle which has been positioned at the high end of the frame. After the load has been discharged the cable is pulled upon so as to lower the pivoted section and the car by means of the cable engaging the pulley on the depending part 12. When the pivoted section is in lowered position the cable is slackened so as to permit the car to run down the track to its starting point.

As will be seen when the parts are in dumping position the cable is looped around pulley 15 on the depending part 12 so that when a pull is exerted upon the cable this loop will pull the depending part downwardly into the recessed member and then the pulleys 14 and 15 are adjacent each other.

In order to prevent the car from running away if the cable should break or some other part give away I provide an automatic holding device which consists of a bar 18 having one end pivoted to the frame 3 and having a right angular extending part 19 at its free end which is adapted to engage any one of a series of projections 20 on a rail 2. Thus if the car should start to run down the track the part 19 would engage one of the projections and prevent further movement of the car. If the safety device is not needed it can be rendered inoperative by means of a slotted link 21 which is pivoted to the bar 18 and which has its slot engaging a bolt 22 on the frame 3. The link has a notch 23 therein which when placed in engagement with the bolt 22 will hold the bar 18 out of engagement with the projections 20. This safety device must be moved to inoperative position when the car is to descend and this may be done either by hand or by a cam device or projection located adjacent the high end of the track and adapted to strike the bar 18 and raise it to inoperative position when the car reaches this part of the track.

As will be seen only the one cable is used for drawing up the load, for dumping the load and lowering the car to its position for reloading.

I also provide means for preventing movement of the dumping section of the track

until the car passes over the same. Such means comprises a spring actuated bolt 31 arranged on a stationary part of the track and adapted to engage a yoke 32 which is secured to the dumping section so as to hold said dumping section in lowered position. A cam wheel 33 is carried by the dumping section, the cam 34 of which is arranged to engage an upright finger 35 on the bolt so as to retract the bolt and said cam is provided with a notch 36 for receiving the finger so that the wheel is held against rotary movement as long as the finger is in the notch. A spring 37 tends to hold the wheel with the flange in inoperative position or in a position where it cannot engage the finger. An arm 38 is connected with the cam wheel and said arm is adapted to be struck by a roller 39, carried by a hanger 40 on the car, as the car moves upwardly over the dumping section of the track. This movement of the arm will rotate the cam wheel a quarter turn so as to move the cam thereon into engagement with the finger and to place the notch in a position where it will be engaged by the finger. This will hold the bolt in retracted position and the wheel against movement. The dumping section is then free to move into dumping position and as it moves upwardly the wheel will rise above the finger so as to release the bolt and permit its spring to return it to projected position. The yoke and bolt are provided with beveled portions so that the yoke can pass by the bolt when the dumping section is returned to normal position. The arm 38 is so arranged that it will yield to permit the downward travel of the car but it will be pulled back to normal position by the spring 41. The wheel is provided with a slot 42 for receiving a pin 43 so that the rotary movement of the wheel is limited.

It will thus be seen that the dumping section is locked in normal position until the car starts to travel thereover and then it will be unlocked so that the section and the car can move to dumping position.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A dumping apparatus of the class described comprising an inclined track, a car engaging the same, means at the lower end of the track for permitting a load to be placed upon the car, a dumping section pivotally mounted at the upper end of the track, a guiding pulley at the pivoted point of the section, a depending part at the rear of the section, a recessed member for receiv-

ing said depending part, pulleys carried by the recessed member and the depending part, a cable passing around said pulleys and having one end connected with the car 5 and its other end adapted to be pulled upon to draw the car up the track.

2. A dumping apparatus of the class described comprising an inclined track, a car adapted to travel up the same, said car having hinged sides, an inclined runway at each side of the lower end of the track with which the said sides will engage when in lowered position to form a roadway to permit the car to be loaded and means for pulling the car up the track.

3. A loading apparatus of the class described comprising an inclined track, a car engaging the same, means for permitting a

load to be placed upon the car at the lower end of the track, dumping means for the car 20 at the high end of the track, means for drawing the car up the track and for controlling the dumping means, a spring bolt on the track for engaging a part on the dumping means for holding said means in lowered 25 position, a cam member on the dumping means, a lever connected with the cam member and a part on the car for striking the lever for causing the cam member to retract the bolt to permit the dumping means to 30 operate, the raising and the dumping means carrying the cam member out of engagement with the bolt.

In testimony whereof I affix my signature.

HOWARD E. STILES.
